APPARATUS FOR FACING LEATHER
OR THE LIKE

Harold A. Bernard, Gloversville, N. Y., assignor to
G. Levor & Co., Inc., New York, N. Y., a corporation

Application July 20, 1949, Serial No. 105,710

1 Claim. (Cl. 69—38)

1

This invention relates to apparatus for facing nonmetallic material, and more especially to apparatus for shaving leather.

Apparatus of this type, particularly those for shaving leather, usually have a multi-bladed cutting wheel past which a sheet of leather, for instance, is drawn while it is held in uniform engagement therewith. To attain a cut of maximum smoothness and uniformity on a sheet of leather the blades of the cutting wheel are customarily arranged in relatively narrow spirals about the wheel axis, and there is customarily provided a power-driven emery wheel which is reciprocated along the cutting wheel and sharpens the blades of the latter. However, sheets of leather shaved in these prior apparatus are, despite the above preventative provisions not entirely smooth and often show abrasion or cut marks which render them of no further use or require costly additional treatment in order to save them for further use.

It is an object of the present invention to provide apparatus of this type which shaves leather or the like with such uniformity as assuredly to omit any abrasion or cut marks in the leather.

It is another object of the present invention to provide in apparatus of this type for axial reciprocation of the cutting wheel relative to a reciprocating emery wheel and to a leather sheet being shaved, thereby to attain greater and more uniform sharpness of the cutting edges of the blades of the cutting wheel by reason of the additional relative motion between the latter and the emery wheel, and abrasion-free shaving of the leather by reason of the erasure-like motion thereon of the spinning cutting wheel during its shaving performance.

The above and other objects, features and advantages of the present invention will be more fully understood from the following description considered in connection with the accompanying illustrative drawings.

In the drawings:

Fig. 1 is a front elevational view, partly broken away, of apparatus embodying the present invention;

Fig. 2 is a side elevation, partly in section, of the same apparatus; and

Fig. 3 is a fragmentary section taken substantially on the line 3—3 of Fig. 1.

Referring to the drawings, the reference numeral 10 designates apparatus which is constructed primarily for shaving leather, but which may also be used for planing or shaving other materials which are similar to leather. The apparatus

2

10 comprises a main frame 12 on which are mounted a cutting wheel 14, a work support 16, a reciprocating carrier 18 for an emery wheel 20, a power drive 22 for the cutting wheel 14 and carrier 18, and a reciprocator 24 for the cutting wheel 14. The main frame 12 of the instant apparatus, which may be cast, provides spaced upright frame sections 26 and 28, respectively, on which are provided bearings 30 and 32, respectively, for the 10 journal support of the cutting wheel 14.

The cutting wheel 14 comprises, in this instance, a shaft-like core 34 in the periphery of which are suitably secured, as by brazing, a plurality of cutting blades 36 which are arranged spirally about the core 34 (Fig. 1). In conformity with conventional practice, and as shown in Fig. 1, the cutting blades 36 of the wheel 14 are from a point midway of the latter arranged in oppositely spiraling formation so that they will 20 have a tendency to spread an engaging leather sheet longitudinally of the cutting wheel 14 and thereby prevent wrinkling of the leather sheet. The cutting wheel 14 is power-driven in a manner hereinafter described.

25 The work support 16 (Fig. 2) comprises a table-like frame 40 (Fig. 2) having a top 42 and spaced legs 44 which are pivoted on a shaft 46, suitably mounted with its ends in forward extensions 48 of the upright frame sections 26 and 28, respectively. The legs 44 of the work support 16 have downward extensions 50, respectively, that are spanned by a foot treadle (not shown) which, when stepped on, causes retraction of the work support 16 from the cutting wheel 14 into the 30 position shown in Fig. 2. Rolls 54 and 56 are mounted on shafts 58 and 60, respectively, which are suitably journaled with their ends in the opposite legs 44, respectively, of the work support 16 in such proximity to the top 42 thereof that 35 the rolls 54 and 56 hug the adjacent beveled sides of the latter and form curved extensions thereof. As usual in apparatus of this type, the work support 16 is spring-urged against an adjustable stop (not shown) into an operating position in which 40 the roll 56 is sufficiently spaced from the periphery of the cutting wheel 14 to admit a leather sheet into uniform engagement with the latter. It is further customary in apparatus of this type to provide a foot-release latch (not shown) which 45 will automatically lock the work support 16 in its operative position for a shaving performance of the cutting wheel 14 on a leather sheet as it is passed over the top 42 of the work support into the bite between the roll 56 and the spinning cutting wheel 14. The roll 56 on the work support 50

16 is, in apparatus of this type, and as further described hereinafter, driven in the direction of the arrow 69 in Fig. 2, in order to draw a leather sheet past the cutting wheel 14 while the latter performs its shaving operation thereon.

The carrier 18 comprises a slide 70 and a transport 72 having opposite side grooves (not shown) in which the slide 70 is guided for movement to and from the cutting wheel 14 by means of gibbs 71. The transport 72 is guided for sliding movement parallel to the cutting wheel 14 on a platform 74 of the main frame 12 by gibbs 76 which are bolted or otherwise secured in place on the transport. The emery wheel 20 on the carrier 18 is in this wise movable with its periphery into and from grinding engagement with the blades 36 of the cutting wheel 14, and is also reciprocable parallel to the latter with its periphery in or out of grinding engagement with the cutting wheel. Movement of the emery wheel 20 into and from grinding engagement with the cutting wheel 14 is accomplished by a gear 80 (Fig. 3) which is mounted on a rotary shaft 82 in the slide 70 and is in permanent mesh with a rack 84 on the transport 72. One end of the shaft 82 extends to the outside of the slide 70 and is there provided with a hand wheel 86 with which to turn the gear 80 for any desired motion of the slide 70 on the transport 72. Interposed between one of the gibbs 71 of the slide 70 and the adjacent guide-groove in the transport 72 may be a wear strip (not shown) which may be forced with more or less pressure against said guide groove by screws 94 (Fig. 2), thereby to adjust the static friction between the slide 70 and the transport 72 so as to prevent self-sliding of the former toward the cutting wheel 14, yet permit its easy movement on the transport 72, when intended, by means of the hand wheel 86.

Reciprocation of the emery wheel 20 along the cutting wheel 14 is accomplished through cooperation between a threaded rotary spindle 88 in the main frame 12 of the apparatus and a threaded follower 90 on the transport 72 (Fig. 3). The spindle 88 is conveniently journaled with its ends in the upright sections 26 and 28, respectively, of the main frame 12, and the follower 90 on the transport 72 projects through a slot 92 which extends in the platform 74 of the main frame 12 between the upright sections 26 and 28 of the latter. The spindle 88 is power driven and is periodically reversed, in a manner hereinafter described, in order to reciprocate the carrier 18 throughout the longitudinal extent of the cutting wheel 14. The emery wheel 20 is mounted on a shaft 98, which is suitably journaled in the slide 70 and provided with a pulley 100 that is drivingly connected with an electric motor 102 through a belt 104. The motor 102 may conveniently be mounted on a platform 106 on the carrier 18.

The power drive 22 comprises a shaft 110 which is suitably journaled in the upright frame sections 26 and 28 of the main frame 12. The shaft 110 may be power-driven from any suitable prime mover (not shown). For driving the cutting wheel 14, the latter carries at its opposite ends pulleys 112 and 114, respectively, which through belts 116 and 118, respectively, are drivingly connected with pulleys 120 and 122, respectively, on the power shaft 110 (Fig. 1).

Firmly mounted on the spindle 88 near one end thereof are pulleys 124 and 126 between which is interposed a freely rotatable idler pulley 128. Passing over two adjacent ones of the pulleys 124, 126 and 128 on the spindle 88 are belts 130 and

132, respectively, which also pass over a pulley 134 on the power shaft 110. One of the belts 130 and 132 is non-twisted, while the other belt, 132 for instance, is twisted (Fig. 2). Cooperating with the belts 130 and 132 is a shifter fork 135 having prongs 136 which straddle the belts 130 and 132 (Figs. 1 and 2). The shifter fork 135 is suitably carried by an actuating bar 140 which is longitudinally slidably supported in the upright sections 26 and 28 of the main frame 12. The actuating bar 140 is provided at spaced points thereof with stop lugs 142 and 144 which cooperate with an arm 146 on the transport 72 in shifting the actuating bar 140 into two end positions, respectively, in which the belts 130, 132 are, through intermediation of the shifter fork 135, shifted onto the pulleys 126, 128 and 128, 124, respectively, on the spindle 88. Thus, assuming that the carrier 18 moves to the left as viewed in Fig. 1 into the end position there shown, the arm 146 will, toward the end of such movement, engage the stop lug 144 and shift the actuating bar 140 to the left so as to bring the belts 130 and 132 from the pulleys 128 and 126, respectively, onto the pulleys 124 and 128, respectively, for reversing the drive of the spindle 88 and, hence, the direction of movement of the carrier 18. Toward the end of the reverse movement of the carrier 18, the arm 146 on the transport 72 will engage the other stop lug 142 on the actuating bar 140 and shift the latter to the right as viewed in Fig. 1, thereby causing a shift of the belts 130 and 132 from the pulleys 124 and 128, respectively, onto the pulleys 126 and 126, respectively, for another reversal of the drive of the spindle 88 and, hence, of the direction of movement of the carrier 18. The motion of the carrier 18 on the platform 74 of the main frame 12 is thus reversed every time the emery wheel 20 reaches the endmost blades 36' and 36'' on the cutting wheel 14.

The previously described roll 56 is driven from a pulley 148 on the power shaft 110 through intermediation of a belt 149, a freely rotatable pulley 150 on the shaft 46 (Fig. 2), and a suitable driving connection (not shown) between the pulley 150 and the roll 56.

In accordance with the present invention, the cutting wheel 14 is in its journal bearings 30 and 32 reciprocated through a relatively small distance at a fairly rapid rate in order to attain maximum sharpness and uniformity of the cutting edges of the blades 36 of the cutting wheel 14, and also to prevent or obliterate any abrasive marks in leather being shaved. To this end, one end of the cutting wheel 14 carries a clevis 152 which is pivotally connected at 154 with one arm 156 of a bell crank lever 158, pivotally mounted at 157 on an arm 159 of the main frame 12. The other arm 160 of the bell crank lever 158 is connected by a link 162 with a strap 164 on an eccentric 166 on the slow shaft 168 of a reduction gearing 170, the fast shaft of which is that of an electric motor 174 which may conveniently be mounted at 176 on a platform 178 on the main frame 12. Thus, the cutting wheel 14 is reciprocated when the motor 174 operates, as will be readily understood.

By reason of the reciprocation of the cutting wheel 14, the much slower reciprocating emery wheel 20 will grind on the peripheries of the cutting blades 36 feather edges which extend beyond the adjacent faces of the respective blades 36 and are exceptionally sharp and uniform, with the result that leather sheets shaved by these blades will show no cut or abrasive marks. The

uniform texture of the shaved leather sheets, which bear not even the slightest indication of the shaving operation to which they were subjected, is further enhanced by the erasure-like motion of the blades 36 of the cutting wheel on the leather sheets while the latter are shaved by the cutting wheel.

While I have shown and described the preferred embodiment of my invention it will be understood that various changes may be made in the present invention without departing from the underlying idea or principles of the invention within the scope of the appended claim.

Having thus described my invention, what I claim and desire to secure by Letters Patent, is:

In apparatus for shaving sheets of leather or the like, the combination of a rotary and axially reciprocating wheel having on its periphery cutting blades extending obliquely to the wheel axis, a support on which a leather sheet is movable past said wheel in uniform cutting engagement with the blades thereof, a grinder reciprocable throughout the axial extent of said wheel in

engagement with the cutting blades thereof to sharpen the latter, means for driving said wheel, means for reciprocating said grinder, a driven eccentric, and a driving connection between said eccentric and wheel for continuously axially reciprocating the latter through a shorter distance and at a higher rate of speed than said grinder.

HAROLD A. BERNARD.
